COMBINATION FISH LINE STABILIZER AND SINKER

Ewell J. Harris, Rte. 3, Box 135A,
Adrian, Mich. 49221

Continuation-in-part of design application Ser. No. 140,008, May 3, 1971, which is a continuation-in-part of design application Ser. No. 23,357, June 8, 1970, now abandoned. This application Dec. 27, 1971, Ser. No. 212,885

Term of patent 14 years

Int. Cl. D22—05

U.S. Cl. D22—30

FIG. 1 is a side elevational view of a combination fish line stabilizer and sinker;

FIG. 2 is a top plan view;

FIG. 3 is a rear elevational view;

FIG. 4 is a side elevational view of a second embodiment of the invention;

FIG. 5 is a plan view of the embodiment shown in FIG. 4; and

FIG. 6 is a rear elevational view of the embodiment shown in FIGS. 4 and 5.

The present application is a continuation-in-part of application Ser. No. 140,008, filed May 3, 1971; which in turn is a continuation-in-part of my parent application Ser. No. D. 23,357, filed June 8, 1970, now abandoned.

I claim:

The ornamental design for a combination fish line stabilizer and sinker, substantially as shown and described.
